UNITED STATES PATENT OFFICE.

WALTER H. YOUNG, OF PITTSFIELD, MASSACHUSETTS, ASSIGNOR OF ONE-HALF TO
JOHN WOODWARD, OF PITTSFIELD, MASSACHUSETTS; JAMES L. EADIE, JR., EXECU-
TOR OF SAID YOUNG, DECEASED.

SPINNING-MACHINE.

1,076,805.

Specification of Letters Patent.

Patented Oct. 28, 1913.

Application filed November 4, 1912. Serial No. 729,244.

To all whom it may concern:

Be it known that I, WALTER H. YOUNG, a citizen of the United States of America, and resident of Pittsfield, in the county of 5 Berkshire and State of Massachusetts, have invented certain new and useful Improvements in Spinning-Machines, of which the following is a full, clear, and exact description.

10 This invention relates to spinning machines and more particularly pertains to certain improvements in spinning frames by means of which certain kinds of fancy yarns designed or intended to be woven into novelty 15 fabrics are produced; that is the yarn produced in the spinning frame under the exercise of this invention is one in which a plurality of strands, rovings or yarns of different colors are twisted together in such 20 a manner that for portions of the length of the yarn one of the strands is helically intertwined with the other, the helical trend or "pitch" of both of the strands being similar 25 while in relatively intermediate intervals in the length of the yarn one of the strands is caused to encircle the other in closely disposed coils or convolutions, thereby giving a spotted or striped aspect to the yarn for the production of novelty effects in the fabric 30 into which the yarn is finally woven.

To this end the invention consists in the provision,—in a spinning machine which may be of the most usual character and which comprises a plurality of yarn supplying spools, a plurality of sets of delivery rolls respectively corresponding to the supply spools, the spindle-carried bobbins on which the yards are wound, and twisting means between the delivery rolls and the 35 bobbins,—of means for imparting relatively intermittent rotary and continuous rotary movement to the different sets of delivery rolls so that in operation the yarns from the different spools at intervals are twisted 40 together on comparatively long and similar helical lines, and then while one of the yarns has its progressive movement toward the bobbin temporarily stopped, the other yarn being continuously delivered is twisted in 45 closely wound convolutions about a given portion of the temporarily stationary yarn, such action being repetitive throughout the 50 time in which the spinning machine runs.

The invention is described in conjunction

with the accompanying drawings and is set forth in the claims.

In the drawings: Figure 1 is a front elevation of a portion of a spinning machine frame equipped with the present improved mechanism. Fig. 2 is a sectional elevation as taken on line 2—2, Fig. 1. Fig. 3 is a partial sectional elevation, on a larger scale, to more clearly show guiding means for the yarn. Fig. 4 is an end elevation of sufficient of the machine to show the means for imparting the continuous and intermittent rotary movements to the two sets of delivery rolls. Fig. 5 is a sectional view, on a larger scale, as taken on the line 5—5, Fig. 1, of a detail of construction to be hereinafter referred to. Fig. 6 represents in side elevation a modified form of the means for imparting the relatively continuous intermittent movements to the two sets of delivery rolls. Fig. 7 illustrates forms of fancy yarns such as may be produced under the working of this invention.

In the drawings, in which a spinning frame of usual construction is shown, A and B represent spools on which yarns of different colors are beamed.

C represents one set of delivery rolls and D represents another set therebelow, these sets consisting of a pair of parallel separated long shafts or rolls a^1 and a^2 and a^3 and a^4 , sectionally formed idler rolls a^5 resting in the cradle-like supports therefor formed by the rolls a^1 and a^2 or a^3 and a^4 , the same always accommodating themselves peripherally to such rolls and assuring proper tension on the yarns running through them so that under the rotative movement positively imparted by one roll of each set, the yarns will be drawn off from the beams A and B, thence passing in engagement with the yarn guides b and b^2 , and thence to the rings d on the ring rail E to be twisted and wound on the bobbins f carried on the spindles g which are individually rapidly driven all as usual.

In the machine here represented, the rolls a^3 and a^4 are continuously driven at uniform speed by means as follows: On the driving shaft F, a spur gear wheel G is affixed, and on the endwise projecting portion of the drawing roll a^3 of the lower set D a spur gear wheel G^2 is provided; the gear train generally indicated by G^3 between the gears

G and G² forming the means for the driving of the one from the other. The drawing roll a³ being thus positively and continuously rotatively driven, its companion roll a⁴ is driven as usual by being geared to it at the opposite end of the spinning frame from that at which the gearing train G, G², G², is located. Thus it is apparent that the yarns coming to the draft action of the set 5 of delivery rolls D will be continuously advanced. The companion rolls a¹ and a² of the upper drawing roll set are likewise geared together at the opposite end of the machine so that the intermittent motion 10 15 positively imparted to one of the rolls a² will cause concurrent motion of the adjacent roll. The roll a² has affixed on its arbor or endwise projecting end a sprocket wheel h alongside which is a loose sprocket wheel k. 20 The driving shaft F has a sprocket wheel m affixed thereon, and a sprocket chain J runs around a fixed sprocket wheel m and the loose sprocket wheel k which is an extension or appurtenance of the drawing roll 25 a²,—such latter sprocket wheel k being merely a guide wheel for the chain.

n represents a chain tensioning wheel. The chain is shown as provided with studs o projecting laterally therefrom for engaging 30 and occasionally imparting rotative movements to the fixed sprocket wheel h, the frequency of this action being determined by the distancing of the studs along the running length of the chain. For 35 steadiness of the running action of the chain, the same as shown in Fig. 5 is provided with the studs o duplicated at opposite sides of the chain, a second fixed sprocket wheel h² being provided on the roll a² 40 at the side of the chain guiding sprocket wheel k which is opposite from the fixed sprocket wheel h. By this duplicated provision of fixed wheels h and h² and the opposite laterally extending studs o, the tendency 45 of the chain and its studs to become skewed is prevented. In the operation when a chain stud o is in engagement with the sprocket wheel h, the set of drawing rolls a² and a¹ will be rotatively operated for the 50 delivery of yarn from the beam A at the same rate as that of the delivery of yarn continuously from the beam B so that at such time under the usual twisting action 55 between the delivery rolls and bobbins, the yarns will be intertwined on comparatively long helical lines; but when the stud passes away from engagement with the sprocket wheel h, the set C of drawing rolls will remain idle and the advancement of the yarn 60 thence forward to the bobbins will temporarily cease, that is until another chain stud arrives to engagement with the sprocket wheel h; and in this time of cessation of the advancing movement of the yarn forward 65 of the delivery rolls C and forward of the

yarn guides b, b², the yarn from the beam B being continuously delivered through and forwardly beyond the set D of delivery rolls and thence to and beyond the guides b, b² will at a point just below such guides be 70 wound around the other yarn in coils so closely disposed to each other as to substantially cover and conceal such other yarn, making a spot thereon in color or aspect contrasting with that which the yarns 75 produced when twisted while running along together at the same speed. Different examples of these fancy yarns are indicated in Fig. 7,—it, of course, being understood that if spots are to be uniformly distanced in the 80 length of the yarn the chain studs will be correspondingly uniformly spaced, while if desired that there should be a non-uniformity of the spacing of the spots there will be a corresponding variation in the spacing of 85 the chain studs.

The mechanism represented in Figs. 1 and 2 is such as would be employed on spinning frames already manufactured and now in use, as the gear train there shown is the usual one; but in cases where the spinning frames in which my invention is to be embodied are newly designed, an arrangement such as represented in Fig. 6 may advantageously be provided, that is to say, one of 90 the rolls a¹ of the upper set would have a pair of sprocket wheels h, h² affixed thereon at opposite sides of the chain guiding wheel k, substantially the same as represented in Fig. 5. One of the rolls a³ of the other 95 drawing roll set would have a sprocket wheel t affixed thereon, the shaft F² would be a power shaft having a sprocket wheel u affixed thereon, and the sprocket chain J² having the studs as before described, here 100 driven by the wheels u, continuously drives the sprocket wheel t and drawing roll set D, and by the studs periodically or occasionally engaging the sprocket wheels, h, h², would 105 impart their intermittent rotative movements to the upper set of delivery rolls. 110

Changes may be made in the details of construction and arrangement of the parts within the scope of my claims without departing from the invention or sacrificing 115 any of the advantages thereof.

I claim:—

1. In a spinning machine, in combination, a plurality of yarn supplying spools, a pair of sets of delivery rolls respectively corresponding to the supply spools, spindle-carried bobbins on which the yarns are wound, twisting means between the delivery rolls and the bobbins, means for imparting continuous rotary movement to the first set of 125 yarn delivery rolls, and means for imparting intermittent rotary movements to the second set of delivery rolls consisting of a sprocket wheel affixed on one of the rolls of said second set, another sprocket wheel, 130

loosely mounted alongside the first named sprocket wheel, a sprocket chain and means for imparting a running course thereto in engagement around the loosely mounted sprocket wheel,—such chain having, at intervals in the length thereof, laterally projecting members for engaging and occasionally imparting rotative movements to the first named, affixed, sprocket wheel.

10 2. In a spinning machine, in combination, a plurality of yarn supplying spools, a pair of sets of delivery rolls respectively corresponding to the supply spools, spindle-carried bobbins on which the yarns are wound, twisting means between the delivery rolls and the bobbins, means for imparting continuous rotary movements to the first set of yarn delivery rolls, and means for imparting intermittent rotary movements to the

second set of delivery rolls consisting of a 20 pair of sprocket wheels arranged in separation and both affixed on one of the rolls of such second set, another sprocket wheel, loosely mounted between said pair of affixed sprocket wheels, a sprocket chain and means 25 for imparting a running course thereto in engagement around the loosely mounted sprocket wheel,—such chain having, at intervals in the length thereof, oppositely and laterally projecting members for engaging 30 and occasionally imparting rotative movements to the affixed sprocket wheels.

Signed by me at Pittsfield, Mass., in presence of two subscribing witnesses.

WALTER H. YOUNG.
